WELL DIGGING APPARATUS

Application filed September 17, 1929. Serial No. 393,279.

The invention is directed to a method of and apparatus for digging wells, particularly oil wells, through percussive or hammering action.

In driving wells through percussive or hammering action, it is extremely difficult if not impossible to eliminate from the plane of action of the hammer the cuttings incident to the hammering action. This is particularly true as in the use of a hammer there is little if any clearance, and in order that the hammer may proceed with an effective result, it is absolutely necessary that the cuttings be cleared. It is, therefore, an important object of the present invention to provide for the effective clearing of these cuttings and in the method described this clearing is effected by the introduction of water under pressure supplemented by the intermingling therewith of air under pressure. Again, when soft material is encountered, particularly where the hammer is acting to some extent against the weight of the column of water used to float the excavated material to the surface, there is such a gripping of the hammer as to materially reduce if not completely interrupt the hammering action.

The improved method broadly directed to overcoming these difficulties is the utilization of a portion of the air directed under pressure for the operation of the hammer as a medium for aerating and thereby reducing the weight of the water column to not only assist in the floatative effect of such column but to use the lighter medium thus created to assist in the return movement of the hammer.

A further object of the invention is the utilization of the aerated water under pressure as a means for inducing a slight rotative movement of the hammer for effective excavation.

A further object is the provision of means for directing a column of aerated water under

pressure into the working plane of and directly beneath the hammer to assist the hammer in its excavating function and also assist the hammer in its return movement following each hammer blow.

A further object of the invention is the provision of means whereby the pipe lines defining the water and air columns may be relatively associated in a manner to permit their convenient withdrawal, with the sections of the air column line sealed at their juncture against leakage and maintained under sealing cooperation by manually adjustable means conveniently accessible at the upper end of the well.

The invention is illustrated in the accompanying drawings, in which:

Figure 1 is a view in elevation of the improved well digging assembly.

Figure 2 is an enlarged sectional view, partly in elevation, of the hammer barrel and the hammer.

Figure 3 is an enlarged vertical sectional view of the casing immediately above the hammer barrel.

Figure 4 is a section on line 4-4 of Figure 2.

Figure 5 is a vertical sectional view showing the means for connecting the sections of the air tube against leakage.

Figure 6 is a bottom plan view of the hammer barrel.

Figure 7 is a vertical sectional view showing the means for connecting the air supply tube and the air tubes and for exerting pressure on the air tubes to seal the juncture between the air tube sections.

The improved well digging assembly includes a tubular well casing 1 made up of a plurality of sections connected by couplings 2 in order that the casing may be added to from time to time as the digging operation proceeds. The lower section of the casing, indicated at 3, is in the form of a barrel for the reception of the hammer parts. These

are primarily conventional, except in the particulars hereinafter specifically referred to, and may be briefly indicated as valve mechanism 4, piston 5, anvil 6, bit piston 7 and tool 6, the bit piston of course being designed to receive different types of bits or tools. The bit piston is circumferentially reduced above its connection with the bit, as at 9, and packing 10 is introduced between the portion 9 10 of the bit piston and the valve.

That portion of the hammer barrel immediately above the upper limit position of the valve is formed with a central vertical passage 11 providing a pressure supply passage 15 for the valve and with a plurality of outer vertically extending passages 12 providing exhaust passages for the valve. The upper end of the passage 11 terminates in a conical enlargement 13 to receive the lower end of 20 the air pipe 14 through which air under pressure is delivered to the valve for the operation of the hammer. The casing section concentric with and above the enlargement 13 is formed with a further conical depression or 25 opening 15, the interior conical wall of which is designed to sealingly and removably receive and cooperate with the lower end of the water pipe 16, which water pipe is in spaced 30 concentric relation with the air pipe 14. The water pipe is made up in sections and the outer surface of the lower end of the lowermost section is beveled, as at 17, in correspondence with the conical wall of the opening 15, so that the water pipe as a whole may, 35 by suitable driving action, be accurately centered and sealed with respect to this wall. The air pipe 14 is also made up in sections and the lowermost section has its lower end beveled in accordance with the inclination 40 of the wall of the enlargement 13, so that under suitable driving action a sealing juncture at this point may be provided.

The respective sections of the air pipe are arranged in sealing juncture with each other 45 to prevent leakage through the means indicated more particularly in Figure 5. As here shown, the respective sections of the water pipe 16 are connected by threaded couplings 18, each provided with an inwardly extending angular flange 19 formed with a series 50 of vertical holes 20 to permit the uninterrupted flow of water, or such flange may be merely in the form of diametrically opposed 55 projections. Each section of air pipe 14 is formed at its upper end with an integral or otherwise secured enlargement 21 having a diameter less than the interior diameter of the coupling 18 with the enlargement includ- 60 ing an upstanding wall 22, the interior diameter of which is greater than that of an air pipe section. The lower end of each air tube section, other than the lowermost section, is formed above such end with an 65 annular flange 23, the exterior diameter of

which is slightly less than the interior diameter of the wall 22.

In assembling the air tube sections, compressible packing 24 is arranged in the space between the lower end of a tube section and the wall 22 of the enlargement of the next lower section, the packing underlying the flange 23. Means are provided, as will later appear, at the upper end of the well for exerting an endwise pressure on the connected air tube sections, thus effectively compressing and distending the packing 24 to completely seal the juncture between the sections of the air tube, and permitting their separation when withdrawal is contemplated 70 by a simple endwise movement.

As previously stated, air under pressure is delivered through the air tube 14 for operating the air hammer and water under more or less pressure is delivered into the 80 water pipe 16 for the flotation of the material excavated by the hammer to the surface of the well.

The method of the present invention aims to take advantage of the air under pressure 90 for the purpose of aerating the water delivered to the bottom of the well in order to increase the buoyant effect of the water and to utilize it in such more or less aerated 95 condition as a means of assisting the displacement of the hammer following each blow both vertically and in rotary movement.

The delivery of the water through the water pipe 16 to the bottom of the well is provided for through a plurality of vertically arranged channels 25 formed in the hammer barrel 3, these channels communicating at their upper ends through inwardly deflected ducts 26 with the lower end of the opening 15 within the plane of the water pipe 16. The upper ends of these ducts are provided with valves 27 which close against a return or upward movement of the water. The air pressure channel 11 leading to the hammer valve is in open communication with the ducts 26, below the valves therein, through passages 28, preferably in the form of tapered jet passages to increase the velocity of the air delivered therethrough, these passages 28 being also provided with non-return valves 29.

Thus, there is a free delivery of water from the water pipe to that portion of the well being operated on by the hammer, and a portion of the air under pressure is delivered to this water column or columns, so that the water is thoroughly mixed with the air before it reaches the bit or tool.

The bit and bit piston are formed with a central water passage 30 which, within the piston, has a lateral section 31 communicating with an annular chamber 32 in the peripheral surface of the bit piston below the packing 10. The wall of the barrel 3 is formed in line with the chamber 32 with

transverse passages 33 communicating at their inner ends with the chamber 32 and at their outer ends with the ducts 26. A portion of the aerated water is thus continuously delivered through the bit and directly onto and in contact with the surface being worked on.

The lower end of the hammer barrel terminates, of course, above the bit in order to permit the necessary reciprocating movement of the bit, and the channels 25, of which there are preferably four, open at equally spaced points through the lower end of the barrel. The upper shoulder of the bit, indicated at 34, underlies the lower end of the barrel and the bit is formed with vertically extending channels 35 which terminate at their lower ends at the bottom of the bit in slightly spaced relation with the central channel 30 and at their upper ends in a plane in vertical alignment with the plane of the lower ends of the channels 25. The channels 35 are preferably three in number and their upper ends are materially enlarged, with 25 the enlargements of downwardly convergent conical form.

As the aerated water under pressure is delivered in a series of streams from the outlet ends of the channels 25, one or more of 30 such streams will engage with one or more of the conical ends of the channels 35, and the force of the water stream will tend to center or align a particular channel 35 with a particular channel 25.

35 At the upper end of the well, water is delivered into the water pipe 16 from a suitable source of water under pressure through a conduit 36 connected with the upper section of water pipe by a union 37. Air is delivered to the air pipe 14 from a suitable source of air under pressure through a pipe line 38. The terminal of the air line 38 is connected to the upper section of the air pipe 14 by a collar 39, housed in an extension 40 of the coupling 37. A packing 41 overlies the collar 39, the packing also seating in an enlarged recess in the extension 40. A gland 42, removably connected to the terminal of the pipe line 38, rests upon the packing 41 and is vertically adjustable with respect to the coupling enlargement 40 through the medium of bolts 43 rising from the coupling enlargement and passing through the gland. Nuts 44 are arranged to engage the bolts to force the gland into sealing relation with the packing 41. Under pressure on the packing and on the collar 39 through this adjustment of the gland, the various packings 24 connecting the respective sections of 50 the air tube within the well are vertically compressed and laterally distended to seal the juncture between the air pipe sections. Thus, the air pipe is rendered a non-leaking continuity by a proper compressive seating of the gland 42.

As previously stated, where the bit or hammer is working in soft semi-fluid material, there is such a decided grip on the tool by this material as to materially interfere with if not completely interrupt the movement of the tool. The weight of the column of water through which the liberated material is floated to the surface is an added pressure against effective tool operation. With the introduction of air under pressure to the water, however, there is a decided buoyant effect or lightening of the water, which not only aids its flotation function but has a decidedly advantageous effect on the bit, particularly when working in material with an inherent tendency to check or stop the bit.

As noted from the preceding description, this aerated water, or water highly charged with air under pressure, is delivered around and beneath the bit. The contained air will have the effect of an inherent pressure medium below and around the lower end of the bit which, by the very reason of this pressure, will tend to materially assist the return or upward movement of the bit and prevent its possible choking when operating in materials of a certain character. Furthermore, this air-charged water, through its increased buoyancy, materially reduces the over-all pressure on the bit and on the material being operated on, and not only assists the separated material in reaching the surface of the well in greater volume in a given space of time but relieves the bit of a pressure against which it would otherwise have to operate in its excavating function.

The method fundamentally apparent from the present application is the introduction of a fluid pressure medium, such as air, for the operation of the hammer and the further introduction of a fluid pressure medium, such as water, as a floatative medium, and introducing a portion of the air under pressure into the floatative medium to increase the floatative function and more particularly for the creation of a reactive pressure on the bit to prevent choking of the latter in use.

The broad feature of the present method that is the aeration of water, is also particularly useful in connection with well digging operations where, from the known geological formation and the depth at which the hammer is working, it is known that the hammer is operating in a "pay formation", or in a stratum desired to be investigated. Under these circumstances, the well digging apparatus described is pulled from the well and the hammer barrel and hammer parts, together with a sufficient length of casing 3 to maintain desired weight on the hammer, is lowered into the well, as for example by a wire-line, after bailing the well. A sufficient length of air hose or other conduit is lowered into the well to communicate with the

vertical passage 11 for supplying air pressure to the hammer and permitting the necessary portion of the air under pressure to bypass into the channels 25. Water is then 5 poured into the well for an appropriate height but there is no further water delivered to the well and no delivery of water under pressure to the well.

As the hammer proceeds with its excavating operation, the air delivered through the hammer and through the channels 25 maintains the water in a constant state of agitation with the internal pressure thereof directed more or less upwardly due to the tendency of the air to rise through the body of water and escape. This agitation, in addition to having all the functions previously ascribed thereto in the direct digging of the well, has the additional function of clearing 20 away the mud, sand and other material surrounding the hammer and causing it to move upwardly in the overlying body of water. This clears the hammer for effective operation and permits a digging through the "pay 25 formation" in a very inexpensive and labor and time saving manner. When the digging has proceeded to the desired or contemplated degree, the hammer with the connected casting parts and air tube is ready and conveniently withdrawn from the well and the well 30 bailed in the usual manner to determine the character of the development.

Here, as in the specifically described well digging operation before referred to, the aeration of the water is a material factor in insuring the flotation of the separated material from around the hammer, for under the tendency of the air to rise in the overlying body of water, there is a continual upward 35 pressure in this body of water which will carry the mud and sand upwardly and maintain it in suspension throughout the digging operation or until such accumulation has practically absorbed the quantity of water provided. This particular method step is regarded as an important detail of the present invention and flows directly from the salient and important features of the initial well digging operation previously described 40 and is to be considered within the purview of the claims forming part of and defining the novel features of this invention.

What is claimed to be new is:

1. A method of excavating oil wells and 55 the like wherein the excavation is carried out through an air-driven tool, consisting in delivering air under pressure for the operation of the tool, delivering water under pressure for the flotation of the separated material, 60 diverting a portion of the air under pressure for mixing with the water, and thereafter delivering the combined air and water mixture to a position beneath the tool.

2. A method for excavating oil wells and 65 the like wherein the excavation is carried out

through an air-driven tool, consisting in delivering air under pressure into the well for the operation of the tool, delivering water under pressure into the well for the flotation of the separated material, forcing a portion of the air under pressure into the water, and delivering the aerated water through the tool and to a point below the tool. 70

3. A well drilling assembly including an air hammer, means for delivering air under pressure to said hammer, means for delivering water under pressure to the bottom of the well, and means for delivering a portion of the air under pressure to the water column above the bottom of the well. 75

4. A well drilling assembly including an air hammer, means for delivering air under pressure to the hammer, means for delivering water under pressure to the well, said means including a series of ducts terminating immediately above the tool of the hammer, means for by-passing a portion of the air under pressure into the water prior to the passage of the water through said ducts, the tool of the hammer formed with a central passage 80 opening through the lower end of the tool, and means for delivering a portion of the aerated water under pressure through said passage in the operation of the hammer. 85

5. A well drilling assembly including an air hammer, a casing for supporting said air hammer, an air pipe for delivering air under pressure to the hammer, a water pipe for delivering water under pressure to the bottom of the well in the vicinity of the hammer, said 100 water pipe surrounding the air pipe, and means for by-passing a portion of the air under pressure from the air pipe into the body of water. 95

6. A well drilling assembly including an air hammer, means for delivering air under pressure to the hammer, and means for delivering a combination of air under pressure and water under pressure to the bottom of the well and directly beneath the hammer. 105

7. A well drilling assembly including an air hammer barrel, a casing connected to and supporting said barrel within the well, an air hammer and cooperating parts arranged within the barrel, air inlet and exhaust ports for the hammer formed in the casing, water channels formed in the barrel beyond the air hammer parts and opening through the bottom of the barrel, means for delivering air under pressure to the air inlet, means for delivering water under pressure to the water channels, and means for directing a portion of the air under pressure into the water prior to its passage through said channels. 115

8. A well drilling assembly including an air hammer barrel, a casing connected to and supporting said barrel within the well, an air hammer and cooperating parts arranged within the barrel, air inlet and exhaust ports for the hammer formed in the casing, water 120

channels formed in the barrel beyond the air hammer parts and opening through the bottom of the barrel, means for delivering air under pressure to the air inlet, means for delivering water under pressure to the water channels, means for directing a portion of the air under pressure into the water prior to its passage through said channels, and means for by-passing a portion of the air and water under pressure through the center of the hammer.

In testimony whereof I affix my signature.
FRED N. STOVER.
